Julie Pomerantz, 50 Sutton Place S., New York, N.Y.

Filed Jan. 26, 1959, Ser. No. 54,309

Term of patent 3½ years

(Cl. D54—12)

Fig. 1 is a top plan view of a spoon or similar article of flatware showing my new design.

Fig. 2 is a side elevational view thereof.

Fig. 3 is a bottom plan view thereof.

Fig. 4 is a section taken on line 4—4 of Fig. 1 and drawn to an enlarged scale.

The essential feature of the invention is shown in full lines in the drawing.

I claim:

The ornamental design for a spoon or similar article of flatware, as shown and described.
